AUTOMATIC FREQUENCY CONTROL
CIRCUITSDudley E. Foster, Morristown, N. J., assignor to
Radio Corporation of America, a corporation
of Delaware

Application March 13, 1937, Serial No. 130,630

7 Claims. (Cl. 250—40)

My present invention relates to automatic frequency control arrangements in general, and more particularly to control circuits adapted accurately to tune superheterodyne receivers at selected station adjustments.

In the past there have been disclosed various types of circuits whose function it was accurately to tune a receiver of the superheterodyne type when the tuning device of the latter was adjusted to a desired station setting. In general such prior circuits employ a discriminator whose function it is to derive a direct current voltage from I. F. (intermediate frequency) energy; the voltage varying in polarity and value with the sense and amount of the frequency departure of the I. F. energy from a predetermined I. F. value. The direct current voltage output of the discriminator is used to vary the gain of a frequency control tube in a manner such that the latter acts to adjust the oscillator tank circuit frequency. The tank circuit frequency is adjusted so as to compensate for the I. F. shift thereby accurately tuning the receiver as soon as the tuning means is adjusted approximately to the desired station setting.

One of the main objects of my present invention is to provide an automatic frequency control circuit with a discriminator deriving direct current voltages from I. F. energy whose frequency shifts from an assigned value; the direct current voltages being employed to vary the operating biases of at least two control electrodes of a frequency control tube whose output circuit and two control electrodes are so electrically related to the oscillator tank circuit as to produce positive and negative reactive effects thereacross.

Another important object of my invention is to provide an improved frequency control tube circuit for the local oscillator of a superheterodyne receiver, wherein alternating voltage developed across an impedance path in the oscillator tank circuit is impressed on the control electrodes of a pair of electron discharge devices, the output currents of said devices being employed to produce reactance effects of predetermined sign across the tank circuit, and means being utilized to control the gain of said devices thereby to regulate the frequency of said tank circuit.

Another object of the invention is to provide in combination with a tuned circuit having an impedance path across which alternating voltage is developed by current flow in the circuit, a pair of electron discharge devices whose electrodes may be disposed in a common tube envelope, the voltage being applied in push-pull manner to the

control electrodes of said devices if the output currents of the latter are to be impressed in parallel on said tuned circuit, or the alternating voltage being applied in parallel to said control electrodes if the said output currents are to be impressed in push-pull fashion on said tuned circuit.

Still other objects are generally to improve the efficiency and operation of automatic frequency control circuits for superheterodyne receivers, and more especially to provide frequency control circuits capable of reliable functioning and economical in construction.

The novel features which I believe to be characteristic of my invention are set forth in particularity in the appended claims; the invention itself, however, as to both its organization and method of operation will best be understood by reference to the following description taken in connection with the drawings in which I have indicated diagrammatically several circuit organizations whereby my invention may be carried into effect.

In the drawings—

Fig. 1 shows a superheterodyne receiver embodying one form of the invention.

Fig. 2 illustrates a modification.

Fig. 3 shows the circuit arrangement of Fig. 1 applied to a different type of frequency control tube.

Referring now to the accompanying drawings, wherein like reference characters in the different figures designate similar circuit elements, Fig. 1 shows in conventional form a superheterodyne receiver to which the invention is applied. In general, the receiver may comprise the usual signal collector followed by one or more stages of tunable radio frequency amplification, and the receiver tuning range may cover 550 to 1500 k. c. (the broadcast band) or the receiver may be of the multi-band type. The amplified signals are fed to a first detector, or mixer, 1 provided with a tunable input circuit 2. The tuning condenser 3 is included in the circuit; its rotors are mechanically coupled, in the well known manner, to the same tuning shaft carrying the radio amplifier and local oscillator tuning condenser rotors. Local oscillations are impressed on the mixer 1 by a local oscillator 4; the latter is provided with a tunable tank circuit 5. The coil 7 and condenser 6 comprise the latter, and it will be understood that the oscillator may be of any well known construction. The low alternating potential side of the tank circuit 5 is shown grounded, and it will be understood that the tank circuit is

connected between the grid and cathode of the oscillator tube as in the usual oscillator circuit. The numeral 8 denotes the local oscillation injection path to the first detector.

The numeral 9 represents the uni-control device for simultaneously adjusting the positions of the rotors of condensers 3 and 6 to tune the signal and oscillator circuits through the receiver frequency range. Those skilled in the art are fully aware of the need for maintaining the frequency ranges of the signal circuits (as circuit 2) and oscillator tank circuit respectively different by a desired I. F. value. The usual padder condensers would be employed in the oscillator tank circuit 5 to maintain the I. F. constant in value at all settings of device 9. The I. F. energy may be given a frequency value chosen from a range of 75 to 465 k. c. The I. F. energy output of first detector 1 is transmitted through one, or more, I. F. amplifiers 10 to the second detector. The latter circuit is not shown since those skilled in the art fully appreciate its construction and that of the following networks; the second detector may be followed by one or more audio amplifiers and terminated by a reproducer of any desired type. The I. F. output circuit 11 is not only coupled by condenser 12 to the second detector, but is coupled to the "discriminator" which derives the direct current voltages, of requisite polarity and value from the I. F. energy.

The frequency control tube 21 is controlled in its effect on the frequency of the tank circuit 5 by the AFC (automatic frequency control) voltage produced by the discriminator. In general as the tuning device 9 is adjusted to a desired station setting, the effect of the AFC circuit is to "pull" the oscillator tank frequency towards that frequency which will produce I. F. energy of the operating value. The same action happens if the local oscillator frequency shifts at a desired setting of the tuning device 9. The tuning mechanism of the receiver may, if desired, be of the type shown in my application Serial No. 73,998, filed December 23, 1935.

Considering, now, the details of the AFC networks, the discriminator comprises a pair of diodes 13 and 14; these diodes, if desired, may be embodied in a 6H6 type tube. There is connected between the anode and grounded cathode of diode 13 a series path including tuned circuit 15 and resistor 18; the bypass condenser 17 being connected across the resistor 18. Between the anode and grounded cathode of diode 14 is connected the tuned circuit 16 and resistor 20 arranged in series; bypass condenser 19 being connected across the resistor 20. Each of the tuned circuits 15 and 16 is magnetically coupled to the I. F. tuned circuit 11. However, one of the diode input circuits is resonated to a frequency above the assigned I. F. value, whereas the other diode input circuit is resonated to a frequency below the I. F. value. In this way a shift in I. F. value from the assigned frequency results in production of direct current voltage across that diode resistor which is connected to the diode input circuit resonated in the direction of shift. The voltages across resistors 18 and 20 are negative with respect to ground.

The frequency control tube 21 is of the 6A6 type; it is a double triode tube provided with a common cathode. The cathode is grounded through coil 22; plate voltage is applied to the plates of the tube through choke 36. Both plates are connected by a common lead 23 through the isolating condenser 35 to the high alternating

5 potential side of the oscillator tank circuit 5. The grids 24 and 25, of the two triodes, are not only subject to the direct current voltages of the discriminator diodes, but have, in addition, impressed thereon alternating current voltages developed across the reactive path in the tank circuit 5. The said reactive path includes resistor 26, condenser 27 and condenser 28 arranged in series between the high alternating voltage side 10 of tank circuit 5 and ground. The grid 24 is connected by lead 29 to the junction of resistor 26 and condenser 27; the grid 25 is connected to the grounded side of condenser 28 through condenser 30. The grids 24 and 25 have applied to them positive and negative alternating current potentials produced by the flow of oscillator current through the path 26-27-28.

The grid 24 is connected by lead 31 to the anode side of diode resistor 20; the resistor 32 included in the AFC lead 31 functions to suppress all pulsating components in the bias voltage applied through lead 31. The AFC lead 33, which includes filter resistor 34, connects grid 25 to the anode side of diode resistor 18. In this way the discriminator functions to control the current flow from tube 21 to the oscillator tank circuit 5. The tube 21, in so far as alternating current is concerned, has a push-pull input connection to the path 26-27-28 across the tank circuit 5, 30 whereas the output electrodes of the tube 21 are connected in parallel relation to the tank circuit.

From a generic viewpoint the action of the control tube 21 is to produce, or simulate, across the tank circuit 5 positive and negative inductive reactances. The presence or absence of a simulated reactance of predetermined sign depends upon the AFC bias. In other words, the magnitude and sign of the reactance produced across the oscillator tank circuit 5 not only depends upon 35 the alternating voltage applied to one of the grids of tube 21, but it also depends upon the magnitude of the AFC bias. When the output frequency of first detector 1 is that to which circuit 11 is tuned, the voltages across resistors 18 and 20 are equal by virtue of the fact that circuits 15 and 16 are symmetrically spaced in resonant frequency on each side of the normal frequency, and, therefore, the net effect of tube 21 on the 40 oscillation frequency of circuit 7-6 is nil. Circuit 16 should be tuned to a frequency higher than the normal I. F. by approximately 4 k. c., and circuit 15 lower than normal I. F. by the same amount. If the receiver, then, be tuned so that the oscillation frequency of circuit 5 is too 45 high, the resultant I. F. will be too high, and there will be more energy in circuit 16 than in circuit 15. The negative bias from diode 14 applied to grid 24 will then be higher than that applied to grid 25 from diode 13. The effect of 50 making grid 24 more negative and grid 25 less negative is to increase the effective inductance due to tube 21 across inductance 7, thus decreasing the oscillation frequency until the resultant I. F. is "normal," which means the energy in 55 circuits 15 and 16 is the same. It will be noted that change in signal amplitude changes voltages derived from diodes 13 and 14 together, and since the effect of each side of tube 21 is to vary the frequency in the opposite direction from that of the other side there is no change in oscillation frequency with signal amplitude. If the frequency of oscillator 4 is too low, the effective inductance across circuit 5 is decreased.

It is not essential to the present invention 60 that the frequency control tube having its grids

in push-pull relation to the tank circuit. In Fig. 2 there is shown a modification wherein the grids 24 and 25 of tube 21 are connected in parallel relation to the oscillator tank circuit 5, whereas the plates 40 and 41 of the frequency control tube are connected in push-pull relation to the tank circuit. In this modification the resistor 26' and condenser 27', both arranged in series, are connected in shunt with the tank circuit. Grids 24 and 25 are connected through condensers 43 and 44 respectively, and by means of a common lead 42, to the junction of resistor 26' and condenser 27'. The plates 40 and 41 are connected to the opposite terminals of the primary winding 1' of a transformer whose secondary winding is the coil 1 of the tank circuit. The midpoint of coil 1' is connected to a source of positive potential.

The common cathode of tube 21 is connected to ground through the grid bias network 22'. The AFC lead 31 is connected to grid 24, while the AFC lead 33 is connected to grid 25. In this modification of the invention both grids 24 and 25 are at the same alternating current voltage polarity by virtue of their parallel connection to the junction of resistor 26' and condenser 27'. However, due to the push-pull coupling of plates 40 and 41 to the tank circuit 5, the inductive reactances simulated across the tank circuit will be of different sign. The discriminator network of Fig. 2 differs from that of Fig. 1 in that "side tuned" circuits are not used. The discriminator is similar to that shown in Seeley Patent No. 2,121,103, June 21, 1938, except that the junction of resistors 18' and 20' is at ground potential instead of one of the cathodes. When the frequency of the resultant I. F. differs from that to which circuits 15' and 11 are resonated, the positive potential across one of the resistors 18' and 20' is higher than that across the other, producing an unbalance in the grids of tube 21 and a change in frequency in the direction to bring the I. F. back to normal. The polarity of coil 15' relative to the coil of circuit 11 determines which resistor, 18' or 20', will have to be most positive when the frequency is higher than "normal" I. F. Similarly the polarity of coil 1 determines whether the oscillation frequency will increase or decrease when grid 24 is more positive than grid 25.

The grid 25 is connected by AFC lead 33 to the cathode side of resistor 18'; while the grid 24 is connected by AFC lead 31 to the cathode side of resistor 20'. In the type of discriminator shown in Fig. 2, the coupled circuits 11 and 15' are tuned to the same I. F.; the midpoint of coil 15' is connected to the high alternating potential side of circuit 11 by condenser 16'. The midpoint of resistors 18'-20' is grounded, and the ground point is connected to the midpoint of coil 15''. Condenser 17' shunts resistors 18'-20'. It is not believed necessary to describe the action of the discriminator other than to point out that at resonance the direct current voltages across 18' and 20' are equal in value but opposite in polarity. When the applied I. F. energy shifts in frequency from the assigned frequency, then the drop across 18' or 20' will dominate depending on the direction of shift. This is all clearly described in the said Seeley application, and need not be repeated here.

The arrangement shown in Fig. 3 is similar electrically to that of Fig. 1 for the reason that the input grids of the frequency control tube are connected in push-pull relation to the oscil-

lator tank circuit, whereas the output electrode circuit is connected in parallel relation to the tank circuit. However, it differs from the arrangement shown in Fig. 1 in that the tube 50 which is employed may be of the 6A7 type wherein a single plate 51 has disposed between it and the cathode the various grid electrodes which are to be used for the control functions. The oscillator tube 52 has the tank circuit 5 connected between its grid and cathode. To plate 51 of the frequency control tube 50 is applied the desired positive potential through the tank circuit coil 7. The condenser 53 functions as a padder condenser, and the condenser 54 acts as a direct current blocking condenser. The remaining elements of the oscillator circuit are well known, and need no further description. The series path to ground across the tank circuit 5 includes the resistor 26, condenser 27 and condenser 28. The junction of resistor 26 and condenser 27 is connected by lead 55 and condenser 56 to the control grid 57 of the frequency control tube 50.

The ground side of condenser 28 is connected by lead 58 and condenser 59 to the control grid 60 of the control tube. The cathode of the tube is connected to ground through the radio frequency choke coil 61. The grids 57 and 60 are separated by a positive grid, and the suppressor grid and control grid 57 are also separated by a positive grid. The control grid 57 is connected by lead 31 to the source of negative AFC bias, as by connecting the lead 31 to the anode side of the diode resistor 20 of Fig. 1. The control grid 60 is connected, as by lead 33, to the source of negative AFC bias in the manner shown in Fig. 1.

It will, therefore, be seen that the path 26-27-28 in Fig. 3 provides a means for producing out-of-phase voltage on the grids 57 and 60 of control tube 50. The AFC bias of each of these control grids is so proportioned that in the normal tuning condition, that is when waves of the assigned I. F. are received, the product of the effect of both grids on the mutual conductance of tube 50 and the impedance across condenser 27 or 28 respectively, are equal. In other words if S_{m1} is the mutual conductance of tube 50 due to grid 60, and S_{m2} is the conductance due to the other grid 57, then

$$\frac{S_{m1}}{j\omega C_{28}} = \frac{S_{m2}}{j\omega C_{27}}$$

This relation exists when no differential control bias is applied. If the control characteristics of grids 60 and 57 are different, as they will be in a tube of the 6A7 type, the AFC biases should be similarly proportioned to the control characteristics of grids 57 and 60 by adjusting the value of the diode resistors 18 and 20. The explanation given in connection with Fig. 1 as to the mode of operation of the control circuit is applicable to the modification in Fig. 3.

While I have indicated and described several systems for carrying my invention into effect, it will be apparent to one skilled in the art that my invention is by no means limited to the particular organizations shown and described, but that many modifications may be made without departing from the scope of my invention as set forth in the appended claims.

What I claim is:

1. In combination with a resonant circuit tuned to a desired frequency, an electron discharge tube provided with a cathode, at least two

control grids and an output electrode, an output circuit connected to the output electrode, said resonant circuit being coupled to the output circuit, reactance means connected directly across said resonant circuit for developing alternating current voltage from alternating current flowing in said resonant circuit, means for applying said voltage to said two control grids in out-of-phase relation, and additional means for varying the biases of said grids in opposite polarity sense.

2. In combination with a resonant circuit tuned to a desired frequency, an electron discharge tube provided with a cathode, a plate and at least two control grids arranged in the electron stream to the plate, an output circuit, said resonant circuit being coupled to the output circuit, means connected directly across said resonant circuit for developing alternating current voltage from alternating current flowing in said resonant circuit, means for applying said voltage to said two control grids in out-of-phase relation, additional means for varying the voltages of said grids in opposite polarity sense, and said plate being connected to a point in said output circuit.

3. In combination with a resonant circuit tuned to a desired frequency, an electron discharge tube provided with a cathode, at least two control grids and one output electrode, an output circuit, said resonant circuit being coupled to the output circuit, means connected to said resonant circuit for developing alternating current voltage from alternating current flowing in said resonant circuit, means for applying said voltage to said two control grids in out-of-phase relation, additional means for varying the biases of said grids in opposite polarity sense, said one output electrode being connected to said output circuit, and said control grids being disposed in the electron stream flowing between the tube cathode and said output electrode.

4. In combination with an oscillator provided with a resonant tank circuit, a frequency control tube provided with at least a cathode, a pair of control grids and at least one output electrode, means coupling said output electrode to said tank circuit, a reactive path connected directly in shunt to said tank circuit and developing alternating current voltage from current flowing in said tank circuit, means for applying said alternating current voltage to said control grids, and additional means for varying the voltages of said grids in opposite polarity senses.

5. In combination with an oscillator provided with a resonant tank circuit, a frequency control tube provided with at least a cathode, a pair of control grids and at least one output electrode, means coupling said output electrode to said tank circuit, a reactive path connected directly in shunt to said tank circuit and developing alternating current voltage from current flowing in said tank circuit, means for applying said alternating current voltage to said control grids, additional means for varying the direct current potential of said grids in opposite polarity senses, said reactive path including at least two reactances of the same sign, and the connections between said control grids and said reactances being such that the alternating voltage impressed on the two grids is in phase opposition relation.
6. In combination with an oscillator provided with a resonant tank circuit, a frequency control tube provided with at least a cathode, a pair of control grids and at least one output electrode, means coupling said output electrode to said tank circuit, a reactive path connected to said tank circuit and developing alternating current voltage from current flowing in said tank circuit, means for applying said alternating current voltage to said control grids, additional means for varying the direct current potential of said grids in opposite polarity senses, said reactive path comprising a pair of condensers arranged in series across the tank circuit, and said control grids being connected to points of said condensers which are of opposite phase.

7. In combination with an oscillator provided with a resonant tank circuit, a frequency control tube provided with at least a cathode, a pair of control grids and at least one output electrode, means coupling said output electrode to said tank circuit, a reactive path connected to said tank circuit and developing alternating current voltage from current flowing in said tank circuit, means for applying said alternating current voltage to said control grids, additional means for varying the direct current potential of said grids in opposite polarity senses, said tube including a positive shielding electrode between the said control grids, the cathode of the tube being connected to a point of fixed potential through a radio frequency choke coil, and said reactive path comprising a pair of condensers in series relation across the tank circuit.

DUDLEY E. FOSTER.
